(57) **CLAIM**

The ornamental design for a bit driver tool, as shown and described.

DESCRIPTION

FIG. 1 is a top front perspective view of the bit driver tool showing our new design;

FIG. 2 is a bottom front perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a top front perspective view thereof in a folded position; and,

FIG. 10 is a bottom front exploded perspective view of the bit driver tool with the bit tips removed.

The broken lines are included for the purpose of illustrating portions of the bit driver tool and forms no part of the claimed design. The broken connection lines shown in FIG. 10 depict the path for assembly of the exploded components and forms no part of the claimed design.

1 Claim, 4 Drawing Sheets
